MAGNETOSTRCTION APPARATUS

Eugene J. Cronin, San Mateo, Calif.

Application May 5, 1950, Serial No. 160,224

3 Claims. (Cl. 318—118)

1

My invention relates broadly to magnetostriiction oscillator systems and more particularly to a method of operation and construction of magnetostriiction oscillator capable of operation over a relatively wide frequency range.

One of the objects of my invention is to provide a method of operating a magnetostriiction oscillator in the ultra-sonic frequency range over a relatively wide range of frequencies.

Another object of my invention is to provide a method of assembling a multiplicity of magnetostriective elements in a unit capable of sustaining any one of the frequencies individual to the several magnetostriective elements and operative to develop pressure effects incidental to the operation of the individual magnetostriective elements.

Still another object of my invention is to provide a construction of magnetostriiction device which may be connected in an electrical circuit and which is operative to sustain any one of a multiplicity of frequencies by the operation of a tuning circuit which is associated with the device.

Still another object of my invention is to provide a construction of magnetostriiction device in which a multiplicity of wires each possessing different magnetostriective frequency characteristics are interrelated as a unit and electrically connected in a circuit operative to sustain any one of the individual frequencies characteristic of the multiplicity of magnetostriective wires.

Still another object of my invention is to provide a construction of magnetostriective device constituted by an assembly of spheres of differing diameters each possessing individual magnetostriective frequency characteristics, the assembly being associated with an electrical circuit tunable over a frequency range embracing the frequencies of all of the magnetostriective spheres whereby the magnetostriective assembly may be utilized to sustain frequencies over a relatively wide frequency range.

Still another object of my invention is to provide an improved assembly for a multiplicity of magnetostriective elements, each possessing differing frequency characteristics whereby any one of the individual frequencies of the magnetostriective elements may be sustained.

A still further object of my invention is to provide an assembly of a multiplicity of magnetostriective elements capable of generating magnetostriective pressures over relatively wide frequency ranges of the order of 60,000 cycles, and higher.

Other and further objects of my invention reside in novel technique in the manufacture, pro-

2

duction and utilization of multiplicity frequency magnetostriective units as set forth more fully in the specification hereinafter following by reference to the accompanying drawings, in which:

5 Figure 1 is a schematic view showing the manner of initially assembling the magnetostriective wires preparatory to the compacting of the magnetostriective wires into the apparatus unit of my invention; Fig. 2 is a plan view of the assembly 10 of magnetostriective wires shown in Fig. 1 and illustrating the manner of assembling the wires which possess differing magnetostriective frequency characteristics; Fig. 3 illustrates the manner of carrying out the molding operation for 15 compacting the magnetostriective wires as a unit; Fig. 4 is a schematic circuit arrangement of an oscillator system associated with the magnetostriiction apparatus of my invention; Fig. 5 is a vertical sectional view taken through a modified 20 form of my invention substantially on line 5—5 of Fig. 6 and illustrating the manner of assembling a multiplicity of spheres of differing magnetostriective frequency characteristics in a compact unit; Fig. 6 is a horizontal sectional view 25 through the magnetostriiction apparatus illustrated in Fig. 5, the view being taken substantially on line 6—6 thereof; Fig. 7 is a schematic view of the magnetostriiction apparatus of Figs. 5 and 6, showing the manner of focussing the magnetostriective pressures; Fig. 8 is a diagrammatic view showing the manner in which an individual spherical magnetostriective element operates to concentrate the magnetostriective pressure in a beam; Fig. 9 illustrates the manner in 30 which the magnetostriective pressure effects may be oriented and focussed with respect to a spherical form of magnetostriective element; Fig. 10 schematically shows the manner of assembling a multiple number of layers of spherical magnetostriective elements in a magnetostriiction apparatus embodying my invention; and Fig. 11 is a perspective view of one of the commercial forms 35 of the devices of my invention.

40 My invention is directed to the technique in the art of magnetostriiction whereby a unit formed by a composite assembly of a multiplicity of individual magnetostriective elements may be associated with an electrical circuit responsive to the entire frequency range of the magnetostriective elements for sustaining oscillations generated at any one of the frequencies incidental to selected magnetostriective elements in the composite assembly.

45 Heretofore in the art the application of magnetostriiction techniques has been limited by the 50 disadvantage that in order to change frequency

in an electrical circuit it is necessary to change the magnetostrictive element each time that the frequency is to be changed. Moreover, in the magnetostriction art, as heretofore known, a magnetostrictive element such as a rod tends to fan out a magnetostrictive beam from the end of the rod. By the novel technique of my invention I have been able to attain what I believe to be the highest frequency yet developed in the magnetostrictive art; that is toward the megacycle range above the 60,000 cycle level and at the same time electrically tuning the associated oscillator circuit through a range of frequencies without changing the magnetostriction device. Moreover, by this new technique I have succeeded in focussing the magnetostrictive beam in pin-point proportions and thereby intensifying the power output.

I provide a method of manufacture of a composite magnetostriction unit in which a multiplicity of magnetostrictive wires of differing magnetostrictive characteristics are erected in a mold and caused to stand on one end by polarization of a magnet and are then embedded in this position by the use of a plastic material. When set, the plastic assembly, with the magnetostrictive elements embedded therein, is wound with a coil of wire embracive of all of the magnetostrictive elements, is then inserted over the composite assembly, and connected in an oscillator circuit which is tunable over a wide range embracive of the frequencies of the individual magnetostrictive wires. When the frequency of the oscillator is tuned to the frequency of any one of the individual magnetostrictive elements the corresponding magnetostrictive element resonates with the oscillator and the frequency of the selective magnetostrictive element is sustained and the pressure effects incident thereto generated and utilized.

The magnetostrictive elements may take the form of wires or spheres of various diameters and frequencies. In the case of spheres as the diameter thereof becomes smaller, the frequency becomes higher. These spheres may be made microscopic in size by atomizing molten metal into water or oil. Each size sphere resonates at a specific frequency. A series of varying sizes of spheres built into one large unit can cover a broad band of frequencies which can be tuned from the oscillator control. Due to the physical construction of the sphere it will resonate from a pin-point of its surface. When a multiplicity of spheres of differing diameters with incidental differing magnetostrictive frequency characteristics are formed in a reflecting surface the spheres coact to focus the pressure effects into a pin-point focal point, thereby increasing the efficiency of the device as a pressure generator.

Magnetostrictive force is a type of ultrasonic energy generated when certain kinds of metal, such as nickel rods, are electrically compressed and relaxed at a rapid rate. As a rod is compressed laterally, it extends endwise. When it relaxes it assumes its original state. The force associated with a small change in length is the entire elastic force of the bar. The main obstacle to overcome in developing this energy is not the modulus of elasticity but the viscosity of the bar material. The change of length of a bar under non-resonant conditions is equal to about .25 parts per million. The change at resonance equals $10^{-4}L$, when $L =$ length (Carlin).

Pressure at resonance of a rod can be built up to 280,000 pounds per square inch of surface

(James, University of Texas). It follows then that a resonator six inches in diameter would develop 3,780,000 pounds pressure at resonance.

The frequency of a rod at resonance is determined by its length and composition. At 20,000 cycles per second, a nickel rod would be about 5 inches long. At 60,000 C. P. S. the rod would be 1½ inches long. In practice this has been accepted as the ceiling for magnetostrictive frequencies because of the physical difficulty in handling shorter rods. Another disadvantage of present-day techniques is the necessity of changing resonators to change the frequency.

I have developed a new technique whereby the ceiling has been raised from 60,000 cycles to the megacycle range with resonators which can be conveniently handled. Furthermore, this technique allows tuning over a wide range of frequencies merely by rotating the condenser on the oscillator. In addition, I have developed a technique whereby this energy can be sharply focussed before it leaves the resonator. This leads to the possibility of delivering even greater pressure by concentrating the energy at a pressure point.

From observations I have made on the cavitation process and on ultra-sonic disruption of yeast cells and other material, evidence seems to indicate the existence of a frequency specific for establishing the optimum cavitation conditions for any particular type of material. This supports Carlin's contention that certain optimum frequencies are known which precipitate dust particles from smoke or smog more effectively than others.

Since the elastic limits of the various geological formations vary with their physical characteristics, the specific frequency necessary to cavitate a particular formation might be considered to be a function of the modulus of elasticity of the formation. Also, it seems clear that the frequency specific to cavitate any particular type of geological formation would be specific for the cavitation of all other formations having the same physical characteristics. Thus it seems quite probable that many types of surfaces could be cavitated with magnetostrictive ultrasonic energy by selecting the frequency specific for that particular type of formation to be cavitated. Again, it is obvious that the immediate removal of the powdered cavitated particles would expose each succeeding surface layer of material for cavitation. The continuation of this cavitation and removal process layer by layer should ultimately result in a hole through the material being cavitated.

Cavitation by such high pressure ultra-sonic techniques has industrial applications in practically all types of drilling as, for example, oil-well drilling, tunnel building, mining, and road building and resurfacing. By proper circuitry, a scanning device may be used to detect the frequency best suited for cavitating a particular formation. As long as cavitation is progressing at a predetermined rate, the frequency selector remains locked in position. When cavitation stops, however, the scanning is triggered into operation to select a new cavitation frequency.

In oil-well drilling, as the various strata are pulverized by the cavitation process, the powdered material is removed by a specially constructed suction unit.

In mining, it is necessary to determine the specific frequency for pulverizing the ore in-situ. However, once pulverized, this material is evacu-

ated in the same manner described for oil-well drilling. One important advantage of this technique in mining is that it permits the mining of a vein of ore without removing the surrounding native rock, and other extraneous material, except when necessary to permit passage of the drilling apparatus. This is possible because the materials possessing different physical characteristics have therefore different frequency responses and will not be cavitated in the process. Thus the need for shothole drilling, blasting, mucking, hauling, and milling of tons of valueless earth is largely eliminated.

The drilling of tunnels normally necessitates the use of a special type of mounting equipped with several drilling heads instead of only one. These heads are arranged on a framework so that they may be moved up against the formation to be tunneled as a unit. The procedure for the removal of the cuttings is the same as hereinbefore set forth.

This technique of cavitation at extremely high pressures is applicable to phases of road building, especially resurfacing. A tractor-type unit having a series of batteries of resonators of the type set forth herein, suspended from a rear platform, proceeds over an old roadbed to be resurfaced, one battery of resonators tuned so that they cavitate the roadbed upon contact, while a second battery of resonators operate on a different frequency and are used to level and compress the pulverized surface back into position by the tremendous pressure developed. A third battery of resonators on the same frame is connected to the tar or surfacing material distribution system which causes the surface material to be spread onto the road in an atomized condition at considerable pressure. These techniques allow a more complete pulverizing of the roadbed material and compression of the tar or other surface than has heretofore been attained. With such units it is possible to resurface a road in one operation while driving over it at a slow speed.

Other industrial applications of magnetostrictive ultra-sonic energy devices embodying my invention and operating at selective frequencies will readily suggest themselves, such as laundry and clothes washing equipment where water is forced under pressure against the textiles to be cleaned.

Referring to the drawings in more detail, reference character 1 designates a plate of insulation material arranged for the assembly of the devices of my invention during production. The magnetostrictive wires shown at 2 are cut in relatively short lengths of the order of 1½ inches. The nickel wires are cut to predetermined lengths according to the magnetostrictive frequency characteristics possessed thereby and are set into a mold of insulation material represented at 3. These wires are formed from nickel possessing magnetic properties and they are caused to stand vertically erect on their ends as represented in Fig. 1 by polarization by the bar magnet 4 located beneath the plate of insulation material. A plastic insulation material in the fluid state is poured into the mold 3 around the vertically erect nickel wires 2 and seeps around the wires 2 as represented at 5, and levels off at the top of the mold 3. The wires 2 may be promiscuously arranged within the mold 3 in generally spiral paths, as represented more particularly in Fig. 2. The pouring operation occurs while the wires 2 are maintained vertically erect in the mold 3 by the polarization due to magnet 4.

The plastic is allowed to solidify forming the unit as represented in Fig. 3 wherein the magnetostrictive wires 2 have adjacent ends thereof coplanar and their opposite ends of varying lengths terminating in staggered relation within the solidified plastic 5. Fig. 3 shows the completed magnetostrictive unit in inverted position. The opposite ends of the plastic unit extend in spaced planes substantially parallel to each other. The plastic unit thus formed has a minor vertical axis and a major horizontal axis. That is to say the horizontal axis predominates.

In Fig. 4 I have shown the manner of utilizing the magnetostrictive unit in an oscillator circuit where the unit is encircled by an operating winding 6 which is electrically connected with an ultra-high frequency electron tube oscillator circuit, represented generally at 7. The ultra-high frequency oscillator circuit includes electron tube 8 having cathode 8a, control grid 8b and anode 8c, wherein the input and output circuits are coupled through the electrical winding 6 which encircles the magnetostriction unit of my invention. The oscillator circuit 8 includes source of anode potential connected at terminals 9 through radio frequency choke coil 10 connected to anode 8c. The output circuit of the oscillator includes condenser 11 connected between anode 8c and one end of the side of the electrical winding 6. The other end of the electrical winding 6 connects to grid electrode 8b and an intermediate tap 11 in electrical winding 6 connected to cathode 8a. The electrical winding 6 and the oscillator circuit 7 are variably tuned by condenser 12 for adjusting the oscillator system selectively over the resonant range of the several magnetostrictive frequencies possessed by the magnetostrictive wires 2. By adjusting condenser 12 the frequency of any one of the magnetostrictive frequency characteristics of the several magnetostrictive elements 2 may be selectively sustained. It is unnecessary to remove a magnetostrictive element of one frequency and substitute a magnetostrictive element of a different frequency as heretofore required in the art.

The magnetostrictive unit as shown in Fig. 4 has the electrical winding 6 thereof hermetically protected by the casing of insulation material 14, the opposite ends of which are substantially coplanar with the planes of the opposite ends of the plastic unit 5 which embeds the magnetostrictive wires 2, and because of the fact that the magnetostrictive elements are mounted in plastic 5 these elements are also thoroughly protected within the mold 3. The pressure operating or generating face of the magnetostriction unit is designated at 15.

In Fig. 5 I have illustrated a modified form of my invention in which spheres 16 of magnetostrictive material differing from each other in diameter and correspondingly in magnetostrictive characteristics are promiscuously deposited in the mold 3 during the manufacturing process as hereinbefore described in connection with Fig. 1, and the liquid plastic flowed around the spheres for embedding the spheres in the plastic. As the spheres become smaller the magnetostrictive frequency becomes higher. The spheres might be made microscopic in size by atomizing molten metal into water or oil. The spheres of different sizes resonate at different magnetostrictive frequencies. Thus a multiplicity of magnetostrictive spheres consolidated into one large unit can embrace a broad band of frequencies, any one of which can be selected when the apparatus is

connected in an oscillator circuit as shown in Fig. 4 by adjustment of tuning condenser 12.

Fig. 5 shows the magnetostriction apparatus with the operating or pressure face thereof at 17. Fig. 6 shows more clearly in partial plan view the distribution of the spheres of differing magnetostrictive frequency characteristics.

In Fig. 7 I have shown the manner of focussing the magnetostriction apparatus of Figs. 5 and 6. In this arrangement the mold is formed, as represented at 18, with a parabolic-like reflector back 19 over which the magnetostrictive spheres 16 are promiscuously distributed within the plastic 5. The pressure effects generated by the several spheres are concentrated upon a focal point 20 which is located at the center of an arc joining two sides of the encompassing coil 6. The balance of the structure shown in Fig. 7 is similar to the structures shown in Figs. 5 and 6.

Figs. 8 and 9 are diagrammatical views explaining the generation of magnetostrictive pressure effects by a magnetostrictive sphere, such as 16, and the emanation of such pressure effects. In Fig. 8 the electrical winding 6' is illustrated surrounding the magnetostrictive sphere 16' which serves as a convex lens for directing magnetostrictive energy along the paths designated at 24 and 25. Another movement of the sphere 16' to the position shown in Fig. 9 serves to shift the beam of energy emanating from the magnetostrictive sphere 16' to the directions 24' and 25'.

In Fig. 10 I have shown the manner of arranging a multiplicity of layers of magnetostrictive spheres in plastic 5 for securing the conjoint action thereof. I have illustrated one layer of magnetostrictive spheres at 21, an adjacent layer of magnetostrictive spheres at 22, and a further layer of magnetostrictive spheres at 23. The several magnetostrictive spheres may include spheres of differing diameters and correspondingly different magnetostrictive frequency characteristics.

In Fig. 11 I have shown one of the commercial embodiments of my invention in the form of a circular disc having a thickness sufficient to include a multiplicity of embedded magnetostrictive spheres which are shown at 16 with minute portions of the spherical surfaces thereof extending tangentially to a plane transverse to the end of the magnetostrictive unit.

I have found the magnetostriction apparatus of my invention very effective and efficient in its operation, and while I have described certain of the embodiments of my invention I realize that modifications may be made and I desire it to be understood that no limitations upon my invention are intended other than may be imposed by the scope of the appended claims.

What I claim as new and desire to secure by Letters Patent of the United States is as follows:

1. Magnetostriction apparatus comprising a multiplicity of spheres of differing diameters having differing magnetostrictive frequency characteristics, means for maintaining said spheres in compact relation, an electrical winding embracing all of said spheres, an oscillator circuit connected with said electrical winding, and means for tuning said oscillator circuit over a frequency range embracive of the magnetostrictive frequencies of all of said spheres for selectively sustaining the magnetostrictive frequency of any one of the magnetostrictive frequencies of said spheres and generating pressures incident thereto, the magnetostrictive pressure effects generated by said spheres being focussed at a point disposed in the center of an arc extending between two sides of the electrical winding embracing said spheres.

2. Magnetostriction apparatus comprising a casing of insulation material open at one end and terminating in a circular curved wall at the opposite end, a multiplicity of spheres differing in diameter and differing in magnetostrictive characteristics one from another assembled against said curved wall, a plastic filling for said casing surrounding said spheres and maintaining the assembled position thereof and an electrical winding surrounding said casing within the magnetostrictive fields of said spheres.

3. Magnetostriction apparatus as set forth in claim 2 in which said casing has a cylindrical side wall terminating in a flat plane, said plastic filling terminating in a flat plane coincident with the aforesaid plane and said electrical winding being disposed around the cylindrical side wall of the casing with the focal point of the pressure effects generated by the several spheres lying outside the flat plane of said plastic filling.
